UNITED STATES PATENT OFFICE.

ROSE SCHUESSLER CARLING, OF LOS ANGELES, CALIFORNIA.

PNEUMATIC ABDOMINAL SUPPORT.

1,272,329.

Specification of Letters Patent. Patented July 9, 1918.

Application filed November 6, 1916. Serial No. 129,757.

To all whom it may concern:

Be it known that I, ROSE SCHUESSLER CARLING, a citizen of the United States, residing at Los Angeles, in the county of Los Angeles and State of California, have invented new and useful Improvements in Pneumatic Abdominal Supports, of which the following is a specification.

My object is to improve the details of construction for a pneumatic abdominal support, and especially to provide a pneumatic pad having an elastic face and elastic edges around the metal back.

Figure 1 is a view in perspective illustrating a completely assembled truss provided with the special pad with which the present invention is concerned.

Fig. 2 is an enlarged view in elevation illustrating the pad as adjustably mounted upon the end of a truss frame, and further disclosing the disposition of an inflating valve mounted upon the back of the pad.

Fig. 3 is an enlarged view in section as seen on the line 3—3 of Fig. 2 viewed in the direction of the arrows, and particularly illustrates the specific construction and formation of the pad.

Fig. 4 is a view in enlarged fragmentary section illustrating the edge of the assembled pad showing in a detailed manner the relative disposition of the layers of material embodied in the truss construction.

Referring to the drawings more particularly, 10 indicates a truss frame which may be formed of any construction. One end is provided with a securing strap 11 formed with eyelets 12 by which the frame may be secured around the body of the wearer when in engagement with a screw-pin 13. The screw-pin 13 extends through an adjustable bracket 14 and terminates within the back of a truss pad 15, thereby allowing the pad to be pivotally mounted in relation to the bracket. The outer end of the bracket 14 is provided with an arcuate slot 16 through which a set screw 17 extends to lock the pad in its adjusted position. It will be understood that the truss frame construction and the pad mounting here described are not essential to the present invention and further that a pad of the character disclosed may be utilized in combination with any other preferred securing truss, girdle, or bandage support.

The pad 15 is formed with a rigid back

18 which is preferably of metal and over which a fabric covering 19 is placed. This covering extends over the entire surface of the back plate and is held in its intended position by a suitable adhesive. Mounted upon one side of said plate and secured to the covering 19 by an adhesive is a rubber sheet 20 which serves as the back wall of a pneumatic pad 21. The outer marginal edge of the rubber sheet 20 is drawn over a front wall 22 of the pad and vulcanized therewith. Prior to the positioning of the front sheet 22, a valve body 23 was properly mounted within and through an opening 24 formed in the back plate 18. This body is held in position by a lock-nut 25 and contains an inflating valve 26 which will hereafter be described. After the sheets 20 and 22 forming the pneumatic pad have been united, a marginal rubber strip 27 is bound around the edge of the pad and overlaps the back plate where it is properly secured by an adhesive material. A pad covering 28 formed of a soft fabric is secured by an adhesive to the face of the front pad wall 22 and brought over the marginal strip 27 and there secured. After this operation, a sheet 29 of fabric is placed over the back of the plate 18 and around the edges thereof in a manner to bind the edges of the marginal strip 27 and the fabric 28.

The pad 21 is adapted to be inflated through the valve 26 and maintained in its inflated condition by the same means. This valve is cylindrical in shape and is formed with a hollow central portion 30 which is formed with a circumferential slot 31 in communication with a threaded bore 32 of the valve body 23. The outer periphery of the member 26 is threaded throughout its length and has a reduced end portion which forms a clearance channel around the member for the passage of air from the hollow central portion of the valve through an opening 33 in the valve body, this opening being in communication with the interior of the pad. A packing disk 34 of suitable material is secured upon the inner end of the valve member and when the member is screwed into its innermost position this disk will bear upon and positively close the opening 33 to the pad. The valve member 26 is adapted to be manipulated by an inflating stem which is not shown in the drawings and which is formed with ex-

ternally tapered end portions adapted to be wedged into the hollow central portion 30 and allow the valve to be rotated.

In adapting the truss for a particular use, 5 the pad is adjustably fixed to the bracket 14 by the set screw 17, after which it may be inflated to a desired degree of hardness by inserting the tapered end of an inflation stem within the hollow central portion of 10 the valve member 26 and thereafter rotating the member 26 until the packing disk 34 is relieved from the opening 33. By blowing through the inflating stem, air will pass into the bore of the valve body through the 15 slot 32 and around the reduced end portion of said body and will thereafter pass through the opening 33 into the pad. When the desired amount of air has been forced into the pad, the valve stem may be turned 20 to draw the packing disk 34 upon the opening 33 and thereby prevent the leakage of air from the pad. After the pad has thus been prepared, the device may be used as intended.

25 It will thus be seen that the pad here provided is especially valuable for use with surgical apparatus when it is desired to apply a gentle and firm pressure to weakened parts of the human body, and that the pad 30 may be readily adapted for use under various conditions and where varying pressures are required. It will also be noted that, due to the detailed construction of the pad, it not only provides a soft, pliable bearing

surface, but also is formed with yieldable 35 marginal edges which are not liable to become embedded within the flesh and produce undesirable irritation.

While I have shown the pad as applied to a truss frame, it is manifest that it may 40 be mounted on any sort of support.

I claim:

A pad for abdominal supports and the like comprising a metal back, a fabric cover cemented to the metal back, a sheet of soft 45 rubber cemented to the fabric cover upon the inner side of the metal back and having its marginal edge extending beyond the metal back all the way around, a front wall having its marginal edge placed near to the 50 marginal edge of the back plate and within the marginal edge of the rubber sheet and vulcanized, a marginal rubber strip forming a binding around the edge of the back plate and overlapping the edge of the back 55 plate and cemented to the back plate fabric cover and to the marginal portion of the rubber sheet extending beyond the edge of the back plate, a cover of soft fabric cemented to the face of the front wall and 60 extending over the marginal strip forming the soft edge around the back plate, and a pneumatic valve inserted through the back plate and coverings.

In testimony whereof I have signed my 65 name to this specification.

ROSE SCHUESSLER CARLING.
